UNITED RESEARCH CORPORATION, OF LONG ISLAND CITY, NEW YORK, A CORPORA-
TION OF DELAWARE

DIAPHRAGM

Application filed April 10, 1926. Serial No. 101,186.

My invention relates to devices for reproducing sound, and it has a special relation to sound boxes for phonographs.

One object of my invention is to produce a diaphragm for reproducing sound which will be extremely sensitive so as to faithfully reproduce sounds over a wide range of frequencies and at the same time will be of such construction that it will endure constant and prolonged usage without in any manner getting out of order or impairing the excellence of the reproduction.

Another object of my invention is to provide a diaphragm having a central rigid metallic portion of extreme lightness so as to be readily moveable to exert a piston-like action without itself flexing and setting up objectionable vibrations, and an outer relatively thin metallic portion rigid with central portion and readily flexible to facilitate the movement of the central portion.

A further object of the invention is to provide an interlocking joint for securing a central piston-like portion of a diaphragm to a flexible outer portion.

Other advantages of the invention will appear more fully as the description proceeds.

Referring to the accompanying drawings, Fig. 1 is an elevational view illustrating a sound box embodying the invention, detached from the tone arm. Fig. 2 is an elevational view of the opposite side of the sound box shown in Fig. 1. Fig. 3 is a sectional view of the sound box taken substantially on a line 3-3 of Fig. 1. Fig. 4 is a sectional view taken substantially on the line 4-4 of Fig. 1, and illustrating particularly a mounting for the stylus bar. Fig. 5 is a detail central sectional view on a larger scale of the diaphragm embodied in the sound box illustrated in Fig. 1. Fig. 6 is a detail view on a large scale of the outer side of the diaphragm. Fig. 7 is a detail central sectional view of a modified form of diaphragm, and Fig. 8 is a detail view with parts broken away, illustrating a device for securing the stylus bar to the diaphragm.

The sound box illustrated as embodying the invention comprises a casing, a dia-

1 to vibrate the diaphragm, and a mounting 2 (Fig. 2) for supporting the stylus bar for pivotal movement.

The diaphragm comprises a central piston 3, and a flexible annulus 4, on which the piston 3 is supported in its vibratory movement.

To make the piston 3 of extremely low mass it is made extremely thin and is composed of a light substance such as aluminum or an aluminum alloy. In order to prevent flexure of the piston in operation and the setting up of undesirable vibrations therein it may be deformed. The central portion may be given the shape of a cone and a plurality of radial strengthening ribs 5 extending from the apex to the base of the cone may be provided to increase rigidity of the cone. Similarly shorter ribs 6 extending for a short distance from the base of the cone toward the apex may be provided. In order to further prevent flexure of the piston 3, it may also have an annular deformation 7 therein which may be angular in cross section.

The piston 3 may be deformed at its periphery to provide for its securement to the annulus 4, and the parts may be held together by an interlocked joint. A number of tongues 8 may be provided at this peripheral portion and alternate tongues may be spaced apart 80 to receive therebetween the annulus 4. The tongues 8 may extend radially along the opposite faces of the annulus 4.

The tongues may be formed by slitting the piston at its periphery by suitable dies and alternate tongues may be bent outwardly. The annulus may be placed on the unflexed tongues and the bent tongues may then be forced against the face of the annulus and thus caused to securely grip the same.

The annulus 4 is extremely thin to facilitate flexure thereof and is preferably made of a light material such as aluminum or an aluminum alloy. To facilitate flexure of the annulus 4, a plurality of deformations may be provided which may be in the shape of annular concentric corrugations 10.

The corrugations 10 in the annulus may be formed by suitable dies prior to the assembly of the piston with the annulus. Like-

wise the conical shape of the piston, the ribs 5 and 6 and the deformation 7 may be produced by suitable dies prior to assembly.

The outer portion of the annulus 4 may be retained between a pair of washers 11 which may be compressed between a cap 12 and a plate 13. A clamping ring 14 having a threaded engagement with the cap 12 may be provided for holding the latter securely 10 in position.

An aluminum diaphragm having a central rigid portion approximately .004" in thickness and an outer flexible portion approximately .002" in thickness has been found to 15 give excellent results.

Such a diaphragm embodying the invention, is extremely sensitive because of the exceedingly small mass of both the central and outer portions and the readily flexible character of the exterior portion. It therefore, 20 effects the faithful reproduction of sound over a wide range of frequencies without tendency to distortion or the setting up of undesirable vibrations. 6

25 Yet, notwithstanding its extreme sensitivity, it is very durable and shows no tendency to deteriorate even after long usage. The piston does not tend to collapse, but retains its shape permanently.

30 In a modification of the invention, as shown in Fig. 7, a deformation 40 may be provided in an annulus 41 and a central piston 42 which may have the shape of a cone, may be secured thereto by tongues 43 adjacent the 35 base of the cone. The tongues 43 may be similar to the tongues 8 of the modification previously described. Annular corrugate deformations 44 may also be provided in the annulus 41 to facilitate flexure thereof.

40 The face of the plate 13 is spaced slightly from the diaphragm to provide a shallow air chamber and may be provided with an annular recess 15 adjacent the outer base of the deformation 7 to permit the diaphragm to 45 move toward the plate 13. The plate 13 may also have an annular rib 16 adjacent the deformation 7 which will permit movement of the diaphragm but reduce the volume of the air chamber so that it may be made quite 50 small. The inner face of the rib 16 may converge into a throat 17 of small diameter.

For securing the stylus bar 1 to the piston 3 the central conical portion of the piston may be provided with an aperture 18 adjacent its 55 apex to receive the shank 20 of a rivet which may be provided with a head 21 for engaging the piston. The rivet may be composed of a light metal such as aluminum or an aluminum alloy and may clamp a ring 22 of suitable 60 metal such as brass against the piston which may be slightly flattened at its apex so as to be securely gripped by the ring and the head of the rivet. The ring 22 may be countersunk at 23 to permit the rivet to be spread 65 therein.

The stylus bar may be made of suitable material such as steel and may be rigidly secured to the ring 22 by solder 24. The stylus bar may be dished at 25 to provide room for the spread end of the rivet and may have flattened terminals 26 seating snugly against ring 22. 70

It will be apparent that the described means for securing the stylus bar to the diaphragm will have a minimum weight as the parts are small and of minimum mass. The sensitiveness of the diaphragm and its readiness to respond to the impulses of the stylus bar are greatly enhanced yet at the same time the stylus bar is secured rigidly to the diaphragm in such a manner that there is no possibility of the stylus bar tearing loose. The secure clamping of the diaphragm between the ring 22 and the head 21 of the rivet prevents the possibility of parts tearing loose 80 or setting up undesirable vibrations. 85

The stylus bar may have a pair of oppositely extending tapered trunnions 27 thereon for supporting the same. Each trunnion may be surrounded by and rotate on a series of 90 balls 28 in a bearing 30 on the cap 12. A follower 31 may be provided in each bearing, having a recess 32 to receive the end of the trunnion 27. Each follower 31 may have a circular tapered portion for engaging the 95 balls.

A single leaf spring may be provided for moving the followers inwardly to cause them to press upon the balls and thus take up looseness of parts. The spring may have terminals 34 directly engaging the followers 31 and may have bends 35 adjacent its terminals spaced slightly away from the bearings 30 to permit facile movement of the ends of the spring so that the followers may be adjusted 100 longitudinally in position. This permits the adjustment of the position of the stylus bar in a direction longitudinally of the trunnion 27 so that the stylus bar is relieved of all 105 strain and is permitted to move frictionlessly 110 in its vibrations.

A feature of the stylus bar mounting is the tendency to automatically take up looseness of the balls or trunnions. The spring urged followers maintain the balls constantly in 115 intimate contact with the tapered trunnions so that the possibility of chattering and setting up undesirable vibrations in the movement of the stylus bar is eliminated. The 120 spring pressure is light and the taper of the trunnions is such as to prevent undesired wedging of the balls or the development of friction which would interfere with the free movement of the stylus bar.

The bearings 30 may have longitudinal 125 grooves 36 therein in which the spring may be seated, and the spring may be bowed centrally at 37 to impart resiliency to it, and facilitate its assembly and secure retention in place. 130

The invention is not limited to the embodiment illustrated and described. The diaphragm and other features thereof may be embodied in loud speakers, telephones, etc., 5 nor is it essential that the diaphragm should be made of two separate parts nor that the annulus 4 have deformations therein. A substantial range of equivalents is contemplated within the scope of the appended claims.

10 I claim:

1. A diaphragm comprising a single ply central portion approximately .004" in thickness, and an outer portion approximately .002" in thickness, having a deformation to 15 facilitate flexure, both of said portions being composed of a metallic substance as light in weight as aluminum.

2. A diaphragm comprising a central rigid member, and an outer annular member, said 20 central member having radially extending portions spaced apart to receive and grip said outer member therebetween and of sufficient rigidity to securely hold said outer member by reason of the mechanical or gripping action of said portions.

3. A diaphragm comprising a central rigid member having a deformation therein to prevent flexure thereof, and an outer relatively thin flexible member having an opening 30 therein to receive said central member, both of said members being metallic, said central member having radially extending tongues

thereon to grip opposite faces of said outer member, and secure said members together.

4. The method of making a diaphragm which comprises assembling an outer diaphragm member having an opening therein 70 about a central diaphragm member, and bending one of said members to cause it to grip the adjacent edge of the other and secure said members together.

5. The method of making a diaphragm 75 which consists in bending a peripheral portion of a central diaphragm member inwardly to permit the assembly of an outer annular diaphragm member against another peripheral portion of said central member, assembling said outer member in position against the second mentioned peripheral portion, and bending the first mentioned peripheral portion to cause it to grip said outer member.

6. The method of making a diaphragm which comprises cutting radial slots in a rigid central diaphragm member to produce a series of radially extending tongues, flexing alternate tongues to permit the assembly of an 90 outer diaphragm member against the unflexed tongues, positioning said outer diaphragm member against said unflexed tongues, and flexing the bent tongues to cause them to grip said outer member. 95
